Charles E. Henry

UNITED STATES PATENT OFFICE.

JESSE M. McHENRY, OF DETROIT, MICHIGAN.

HUMIDIFIER.

Application filed April 25, 1921. Serial No. 464,301.

To all whom it may concern:

Be it known that I, JESSE M. McHENRY, a citizen of the United States, residing at Detroit, county of Wayne, State of Michigan, have invented a certain new and useful Improvement in Humidifiers, and declare the following to be a full, clear, and exact description of the same such as will enable others skilled in the art to which it pertains 10 to make and use the same, reference being had to the accompanying drawings, which form a part of this specification.

This invention relates to humidifiers and a particular use for which the invention may 15 be applied is in conjunction with hot air furnaces for humidifying the air prior to discharge into the air pipes of the heating system. The object of the invention is to provide a simple and inexpensive device including a vaporizing pan and a supply tank for supplying water thereto as it is evaporated by the heat of the furnace. A further object is to provide, in conjunction with the tank and evaporating pan, a means for 20 varying the surface area of water exposed to the influence of the heat of the furnace whereby the relative humidity of the air may be varied as may be deemed desirable. An additional object is to provide an apparatus of the character described in which the supply tank is mounted exteriorly of the furnace and adapted to fill an intermediate tank from which the evaporating pan is 25 supplied with water. These and other objects and the several novel features of the invention are hereinafter more fully described and claimed, and the preferred form 30 of humidifier embodying my invention is hereinafter clearly shown in the accompanying drawing in which—

Fig. 1 is an elevation partly in section showing my improved humidifying device in its general relation with a furnace.

Fig. 2 is a section taken on line 2—2 of Fig. 1 showing the supply and intermediate tanks and vaporizing pan.

Fig. 3 is a detail showing a section of a vaporizing pan and indicating the manner in which the vaporizing surface of the water 50 may be increased or decreased in the pan.

The apparatus may be used in various ways wherever vaporization is required in the humidifying of air, a specific instance of

which is shown in the drawing in which 1 indicates a furnace of what is known as 55 "hot air" furnace having the usual fire and ash doors and fire-pot 2. Between the fire pot 2 and casing 1 is the hot air space of the furnace and in this space I have positioned a vaporizing pan 4 which as shown partic- 60 ularly in Fig. 3, is V shaped, the walls forming an angle preferably at least as great as ninety degrees for a purpose hereinafter more fully described. This pan may be supported in any approved manner in the air 65 chamber 3 and may be fixed therein or adjustable therein as desired. Preferably, the pan is supported by a bracket 5 provided therefor and secured to the casing for the furnace and the pan is curved length-wise, 70 as shown more clearly in Fig. 2. A pipe 6 is connected to the bottom of the pan and extends therefrom through the casing of the furnace and is connected to an intermediate or auxiliary tank 7. The main 75 water tank 8 is supported outside of the furnace on a standard 9 therefor but may be supported in any other manner if desired, and this tank is provided with a valved filling device 10 at the top through which 80 the tank may be filled with water and is also provided with an air vent valve 11 at the top. The tank is further provided with a gauge glass 12 connected to the top and bottom of the tank respectively whereby the 85 amount of water in the tank may be shown. A normally open faucet 13 is provided at the bottom of the tank and when the tank is positioned on the support 9 to the conduit 13 is directly over the intermediate tank 7, 90 as shown in Fig. 1, and discharges thereinto. An air tube 14 is provided opening into the top of the tank 8 and this tube extends downward into the intermediate tank 7. The tube 14 is preferably a flexible metal 95 hose or soft metal tube having a lower end extending downward into the intermediate tank 7, the tube being flexible so that the lower end thereof may be adjusted vertically whereby the distance to which it ex- 100 tends into the intermediate tank may be varied to vary the depth of liquid therein which, in effect, varies the evaporating surface of the water within the vaporizing pan.

In operation the faucet 13 is closed by

means of a cock 18 and while this cock is closed the tank is filled with water at which time it is necessary to open the air vent 11. When the tank has been filled the vent valve 11 and the filling valve 10 are closed and the valve 18 opened. This permits the water from the tank to flow into the intermediate tank 7 through the faucet 13 and water will flow from the tank as long as air may flow upward through the tube 14 into the top of the tank to replace the discharged water. As the level of water in the intermediate tank reaches the bottom of the air tube 14 the air tube is closed preventing further flow of air into the tank whereupon discharge of water through the discharge faucet 13 closes. It will be noted that by thus filling the intermediate tank 7 the water will pass through the pipe line 6 and fill the vaporizing pan 4 to the level in the intermediate tank 7. As the water vaporizes due to the heat in the furnace and the level thereof in the pan and intermediate tank falls below the mouth of the tube 14 opening 25 the same to atmosphere, additional water will flow through the pipe 13 into the intermediate tank which is thus maintained normally supplied; thus keeping the vaporizing pan normally supplied as long as water is provided or supplied to the tank 8.

The rapidity with which the water in the pan vaporizes depends upon the surface thereof exposed to atmosphere. To increase or decrease the relative humidity of the 35 heated air passing from the furnace I have provided a means for adjusting the length of the air tube 14 by the flexibility thereof whereby it may be made to extend into the intermediate tank to a greater or less depth. 40 With the pipe 14 extending into the intermediate tank to the position as shown in Fig. 3 the surface of the water within the vaporizing pan exposed to air is of a certain extent. By raising the lower end of the tube 45 14 within the intermediate tank for instance to the extent shown by the dotted line *a* in Fig. 3, a greater surface of water may be exposed to atmosphere in the vaporizing pan whereby a greater amount of moisture may 50 be provided in the air passing through the furnace and this adjustment may be secured in various ways the preferred form of construction being shown in the drawings. From the foregoing it can be readily seen that the 55 greater the depth to which the tube 14 extends into the intermediate tank the less the evaporating surface of the water within the vaporizing pan and, by raising the tube 14 within the water within the vaporizing pan 60 the evaporating surface of the water is increased owing to the V shape of the pan thus increasing or decreasing the evaporating surface and relative humidity of the air passing from the furnace.

65 As the evaporation is comparatively slow

there is no need for any great amount of water to flow into the vaporizing pan at any time and therefore the faucet 13 and air tube 14 need not be greater than about one-eighth of an inch in internal diameter. These tubes 70 should be of small diameter for the further reason that tubes too large in diameter will permit too ready a flow of water which is not efficiently controlled by closure of the air tube by the water in the intermediate 75 tank.

From the foregoing description it becomes evident that the device is very simple and efficient in operation, comparatively inexpensive in form, and automatic in operation 80 as long as the tank is supplied with water and provides a device which accomplishes the objects desired.

Having thus briefly described my invention, what I claim and desire to secure by 85 Letters Patent of the United States is—

1. A humidifying device comprising the combination with a furnace having a casing, a fire box and a hot air space therebetween, of an evaporating pan in the hot air space 90 supported by the casing and spaced from both the casing and fire box, an auxiliary tank exteriorly of the furnace, a conduit extending through the casing connecting the auxiliary tank and evaporating pan, a water 95 supply tank mounted independently of the auxiliary tank having a valved discharge outlet at the bottom through which water may discharge into the auxiliary tank, and an air conduit leading into the top of the 100 supply tank having an end depending into the auxiliary tank and constructed to permit variation of the distance to which the said conduit extends into the auxiliary tank.

2. A humidifying device comprising the 105 combination with a furnace having a casing, a fire box and a hot air space therebetween, of an evaporating pan in the hot air space substantially V shaped in cross section and curved lengthwise supported by the casing 110 and spaced from both the casing and fire box, an auxiliary tank exteriorly of the furnace, a conduit extending through the casing connecting the auxiliary tank and evaporating pan, a water supply tank mounted independently of the auxiliary tank and having a discharge faucet at the bottom for discharging water into the auxiliary tank, a flexible air conduit leading into the top of the supply tank and having an end depending into the auxiliary tank, and a valved vent device for the supply tank at the top.

3. A humidifying device comprising the combination with a furnace having a casing, fire box and a hot air space therebetween, of 125 an evaporating pan V shaped in cross section and arcuate in form positioned in the air space and spaced from both the casing and fire box, an auxiliary tank on the exterior of the casing, a conduit extending 130

through the casing connecting the auxiliary tank and evaporating pan, a water supply tank outside of the furnace, a faucet therefor extending over the auxiliary tank and adapted to discharge thereinto, and an air conduit leading into the top of the supply tank and having a depending end extending

into the auxiliary tank, said end being variable in position to vary the level of water in the auxiliary tank and evaporating tank. 10

In testimony whereof, I sign this specification.

JESSE M. McHENRY.
